UNITED STATES PATENT OFFICE.

GEORGE T. SHEARER, OF WAYNESBORO, PENNSYLVANIA.

DIE-HEAD.

1,397,238.

Specification of Letters Patent.

Patented Nov. 15, 1921.

Application filed March 20, 1920. Serial No. 367,546.

To all whom it may concern:

Be it known that I, GEORGE T. SHEARER, a citizen of the United States, residing at Waynesboro, in the county of Franklin and State of Pennsylvania, have invented certain new and useful Improvements in Die-Heads, of which the following is a specification.

The present invention relates to die heads, and more particularly those employed in threading rods, bolts and the like. The primary object is to provide a structure that is exceedingly compact and relatively simple, the parts being effectively supported at all points so as to obviate any danger of yielding on the part of the cutters, with consequent defective work.

A further and important object is to provide a structure which can be readily altered to cut either right or left-hand threads and which can be easily adjusted to operate on work of different diameters.

In the accompanying drawing which shows the preferred embodiment of the invention, Figure 1 is a front elevation of the head with one of the cutters removed from its holder and one of the holders removed from its carrier.

Fig. 2 is a view partly in side elevation and partly in longitudinal section,

Fig. 3 is a detail sectional view on the line 3—3 of Fig. 1,

Figs. 4 and 5 are sectional views on the lines 4—4 of 5—5 of Fig. 3,

Fig. 6 is a face view of one of the cutter holders,

Fig. 7 is a side elevation of the same, and Fig. 8 is an end view.

Similar reference numerals designate corresponding parts in all the figures of the drawings.

In the embodiment disclosed, a body is employed consisting of a head 9 and a shank 10, said body having an axial work-receiving bore 11. The body is provided on different sides of the bore 11 with a plurality of sockets 12 having reduced rear portions 13, and in these sockets are rotatably mounted carriers in the form of gudgeons 14 having reduced stems 15 in the reduced portions 13 of the sockets. The carriers are held in place by any suitable means, as for example, retaining disks 16 mounted on the rear ends of the stems 15 and held in place by suitable screws 17. The front faces of

the carriers are flush with the face of the body and are provided with recessed seats in the form of transverse slots 18 that open through the inner sides of the gudgeons, the outer ends terminating short of the outer sides of said gudgeons.

In the seat 18 are adapted to be fitted detachable cutter holders in the form of blocks 19 that snugly fit in said seats and project from the inner open ends thereof. The cutter holders furthermore preferably have sockets 20 in their inner ends that receive posts 21 projecting into the inner ends of the recesses 18, as illustrated in Fig. 2. The cutter holders have longitudinal slots 22 for the reception of the usual cutters 23, and said holders preferably have extensions 24 that back up the projecting portions of the cutters, as illustrated in Fig. 1. The bottoms of the slots 22 are preferably inclined to suit the particular pitch of the thread being cut, as will be readily understood to those skilled in the art. Each of the cutter holders 19 is held in its seat by screws 25 that pass through the holder at one side of the slot 22, and are threaded into the carrier 14, as shown in Fig. 2. Two sets of openings 25^a are provided to receive the screws 25, one set for right hand cutters, the others for left-hand cutters. The heads of these screws overlap the slots 22, and engaging over the cutters 23, serve to also hold the cutters in the holders. Preferably also an intermediate screw 26 is employed that does not pass through the holder 19, but serves as a supplemental fastening to secure the cutter to the holder. Each of the holders is also provided with a longitudinally movable abutment screw 27 threaded into the holder and extending across the slot 22, the said screw thus acting to bear against the rear end of the cutter 23. These screws 27 are accessible for operation through openings 27^a formed in the body and carriers 14.

Each of the carriers 14 is provided directly in rear of the cutter holder seats 18 with oppositely disposed shoulders 28 and 29, and extending from these shoulders are radial sockets 30 adapted to receive plungers 31. The lower ends of each of the plungers are adapted to engage with both of the oppositely disposed shoulders of adjacent carriers, as shown in Fig. 4. The inner ends of the plungers are preferably provided with rounded bearing ribs 31^a and the 110

shoulders are recessed to receive the same, as shown. These plungers 31 have their outer ends beveled as shown at 32, and said beveled ends are adapted to project into keyways 33 formed longitudinally in the periphery of the body 9. An actuating ring 34 surrounds and is longitudinally slidable upon the body 9, being provided with an annular groove 35 for receiving an operating yoke or device not shown. This ring is provided with notches 36 that are alined with the keyways 33, and the bottoms thereof are inclined as shown at 37. Keys 38 are located in the keyways 33 and are secured to the ring 34 by suitable screws 39 and pins 40. The front ends of the keys 38 are beveled to correspond to the beveled bottoms 37 of the notches 36, and these beveled surfaces coöperate with the beveled 20 outer ends 32 of the plungers 31. With this construction, it will be evident that when the ring is moved toward the front end of the die head the beveled bottoms 37 of the notches 36 and the beveled ends of the keys 25 38 will cause the plungers to be moved inwardly and said plungers acting on the shoulders 28 or 29 will turn the carriers to carry the cutters 23 to their operative positions and will hold them positively in such 30 positions.

To swing the cutters outwardly or away from the work the following mechanism is preferably employed. The carriers 14 are provided in rear of the shoulders 28 with other oppositely arranged shoulders 41 and 42, and extending radially therefrom are sockets 43 in which are located coiled springs 44 that bear against the shoulders 41 and 42 respectively. These springs have their 40 outer ends bearing against abutment screws 45 threaded into the sockets and preferably having guide stems 46 extending into the springs. Those springs 44 which are to act in opposition to the plungers 31 are placed 45 under tension by moving inwardly the screws 45 abutting thereagainst, while the tension of the other springs is released by moving the screws bearing thereagainst to their outer limit, as shown.

With the construction as illustrated, it will be evident that when the cutters are in their innermost positions as shown in Fig. 1, each plunger 31 will be at its innermost positions, as shown in Fig. 3, and acting 55 against the shoulders 28. The active springs 44 for each plunger will be under full compression and operating against the shoulder 41 on the opposite side of the carrier to the shoulder 28 against which the plunger 31 bears. When the actuating and holding ring 34 is moved rearwardly, the plungers being released, will permit the compressed springs 44 to react and turn the carriers to move the cutters outwardly and thereby dis- 60 engage the work. In this action not only 65

are the springs 44 which bear against the shoulders 42 inactive, but the shoulders 29 are idle, for being on the same sides of the carriers as the shoulders 31 against which the active springs bear when said springs 70 act to turn the carriers, the shoulders 29 move away from the plungers. Therefore it will be clear that in order to cut opposite threads it is only necessary to remove the die holders and substitute them with a re- 75 versely arranged set, release the springs 44 that bear against the shoulders 41 and compress the springs that operate against the shoulders 42. The plungers 31 will now act against the shoulders 29 which become 80 active in opposition to the springs that bear against the shoulders 42 while the shoulders 28 now are idle.

With this construction it will be noted that the carriers 14, the cutter holders 19 and the cutters are all flush with the face of the body, thereby not only providing a compact relation, but one in which all the parts are effectively supported and reinforced throughout their entire width. Consequently there can be no springing or "give" 90 during the cutting action. The parts are moreover very simple and are entirely and easily available, so that adjustment, substitution and rearrangement can be obtained 95 with ease and expedition.

From the foregoing, it is thought that the construction, operation and many advantages of the herein described invention will be apparent to those skilled in the art, without further description, and it will be understood that various changes in the size, shape, proportion and minor details of construction may be resorted to without departing from the spirit or sacrificing any of the 105 advantages of the invention.

Having thus fully described my invention, what I claim as new, and desire to secure by Letters Patent, is:—

1. In a cutter head, the combination with a supporting body, of a carrier member rotatably mounted in the body and having its outer face substantially flush with the face of said body, said carrier member having a recessed seat in its outer end, and a cutter holder located in said seat and having its outer face substantially flush with the face of the carrier member.

2. In a cutter head, the combination with a body having a central work-receiving bore, of a carrier member journaled in and supported by the body at one side of the bore and having its outer face substantially flush with the corresponding face of the body, said member having an elongated recessed seat in its outer end that opens through the side thereof adjacent to the bore, and a cutter holder detachably fitting in the seat and having its outer face substantially flush with the outer faces of the body and member, said 130

holder having a longitudinal cutter-receiving slot opening through its outer side and through the end adjacent to the work-receiving bore.

5 3. In a cutter head, the combination with a body, of a carrier member movably mounted therein and having an intermediate elongated recessed seat that opens through the side of the member, a cutter holder detachably mounted in the seat and having a cutter-receiving seat, and common means engaging the holder and carrier for securing the holder to the carrier and having a cutter engaging portion to secure a cutter in the 15 seat of the holder.

4. In a cutter head, the combination with a body, of a carrier member movably mounted therein and having an intermediate slot in its outer face opening through one side 20 and forming a recessed seat, a cutter holder detachably mounted in the seat and having an intermediate cutter-receiving recess, and screws that pass through the holder at one side of the seat and engage the carrier to 25 secure the holder thereto, said screws having heads overlapping the cutter receiving recess to secure a cutter therein.

5. In a cutter head, the combination with a body having a work-receiving bore and 30 a plurality of sockets around the same, of carrier trunnions journaled in the sockets and substantially flush with the outer end of the body, the outer ends of the trunnions having elongated recessed seats, cutter 35 holders detachably engaged in the seats and substantially flush with the trunnions, said holders having slots in their outer portions, cutters in said slots, and screws for securing the holders in their seats, said screws 40 overlapping the cutters and holding them in the slots.

6. In a cutter head, the combination with a body, of a carrier rotatably mounted therein, said body having a keyway and a socket 45 opening into the keyway, a plunger in the socket operating on the carrier, and an actuating ring slideable on the body and having a key movable in the keyway and operating on the plunger.

50 7. In a cutter head, the combination with a body having an axial work-receiving bore and a plurality of external longitudinal keyways, of a plurality of cutter carriers journaled in the body around the bore, said 55 body having substantially radial sockets extending from the carriers to the keyways, plungers slideable in the sockets and operating on the carriers, and an actuating ring slideable longitudinally on the body and having keys in the keyways that operate on the plungers.

8. In a cutter head, the combination with a body, of a cutter-holding carrier rotatably mounted therein, oppositely acting yielding 60 devices for operating against the carrier,

means for placing either device under tension or relieving the same therefrom, and means for positively moving the carrier against the action of the device that is under tension.

70 9. In a cutter head, the combination with a body, of a cutter-holding carrier rotatably mounted therein, oppositely acting springs having bearings against the carrier, means for placing either spring under tension or relieving the same therefrom, and means for positively moving the carrier against the action of the device that is under tension.

75 10. In a cutter head, the combination with a body, of a cutter-holding carrier rotatably mounted therein, springs bearing against opposite sides of the body, screws for putting either spring under tension and relieving the other, and means for rotating the carrier in either direction.

80 11. In a cutter head, the combination with a body, of a cutter holding carrier rotatably mounted therein and having opposite shoulders, coiled springs bearing against the shoulders, screw plugs threaded in the body 90 and bearing against the springs, plunger means acting against the carrier, and an actuating device for the plunger means.

85 12. In a cutter head, the combination with a body having an axial work-receiving bore, of carrier gudgeons journaled in the body on different sides of the bore, cutter holders carried by the body, said gudgeons having opposite shoulders, said body having substantially radial sockets extending from the 95 shoulders, coiled springs in certain of said sockets bearing against the shoulders, abutment screws in the sockets against which the springs bear, plungers in other of the sockets bearing against the shoulders, and an actuating ring in the body having means for engaging and moving the plungers.

100 13. In a cutter head, the combination with a body, of a carrier rotatably mounted thereon, spring devices for acting oppositely 110 against the carrier, means for causing either spring device to be active against the carrier and the other inactive, and devices for respectively acting oppositely against the carrier to move the same and respectively made 115 active or inactive by the activity or inactivity of the spring devices.

120 14. In a cutter head, the combination with a body, of a carrier rotatably mounted thereon, springs for acting oppositely against the carrier to respectively turn the same in opposite directions, means for placing tension upon either spring or releasing it from tension, devices for respectively moving the carrier positively in either direction and permanently in position to act upon the carrier, and means for simultaneously moving the devices.

125 15. In a cutter head, the combination with a body, of a carrier rotatably mounted there- 130

in and having sets of oppositely disposed shoulders, oppositely acting springs operating on the opposite shoulders of one set, means for placing either spring under tension and relieving such tension, plungers simultaneously in position to act against the opposite shoulders of the other set, one being maintained inactive with respect to its shoulder by the activity of the spring acting against the corresponding shoulder, and means for operating the plungers.

16. In a cutter head, the combination with a body, of a pair of adjacent carriers rotatably mounted therein, a device in position to simultaneously act on both carriers to turn the same in opposite directions, and spring means acting on one of the carriers to turn it against the action of the device and to turn the other carrier in the same direction as the said device.

17. In a cutter head, the combination with a body, of a pair of adjacent carriers rotatably mounted therein, a plunger operating between the carriers and having its opposite portions in position to engage the same and turn said carriers in opposite directions, and springs that operate respectively against the carrier to turn one in the same direction as it is moved by the plunger and to turn the other in an opposite direction.

18. In a cutter head, the combination with a body, of a pair of adjacent carriers rotatably mounted therein, a plunger operating between the carriers and having its opposite portions in position to engage the same and turn said carriers in opposite directions, a spring operating against the same side of one carrier as the plunger to move the same in the same direction as the plunger acts, and a spring operating against the opposite side of the other carrier to move the latter in

the opposite direction to the action of the plunger.

19. In a cutter head, the combination with a body, of a pair of adjacent carriers rotatably mounted therein, a device in position to simultaneously act on both carriers to turn the same in opposite directions, spring devices for respectively turning each plunger in either of opposite directions, and means for causing certain of said spring devices to be active and the others inactive and vice versa.

20. In a cutter head, the combination with a body, of adjacent carriers journaled therein, a plunger operating between the carriers and having opposite portions positioned to act against the carriers and turn them in opposite directions, oppositely acting springs operating on each carrier for turning the same in either direction, and means for placing either spring under tension or relieving the tension thereof.

21. In a cutter head, the combination with a body, of a circular series of carriers journaled therein, each having sets of oppositely disposed shoulders, plungers between the carriers having opposite portions in position to act against the shoulders of adjacent carriers to turn the same in opposite directions, means on the body for simultaneously moving the plungers, springs operating against other of the opposite shoulders of each carrier, and means for placing tension upon the different springs or relieving them of such tension.

In testimony whereof I affix my signature in the presence of two witnesses.

GEORGE T. SHEARER.
